INTERCHANGEABLE GEAR DRIVE MEANS FOR
ROTARY PRINTING MECHANISM
Walter R. Stelling, Jr., Wauwatosa, Wis., assignor to
Faustel, Inc., Butler, Wis., a corporation of Wisconsin
Filed Jan. 21, 1963, Ser. No. 252,749
7 Claims. (Cl. 101—219)

This invention relates in general to rotary printing press equipment of the type having a plate cylinder, impression cylinder and an Anilox roll. More specifically, the invention relates to an improved gear drive connection between the impression cylinder and the plate cylinder.

One object of the present invention is to provide an improved gear drive unit between the impression cylinder and the plate cylinder, which unit permits the use of the same plate cylinder with at least three interchangeable gears having different numbers of teeth thereon. In this manner the same plate cylinder can be used, for example, in printing jobs requiring 56, 57 or 58 tooth repeat length operations. As a result the number of plate cylinders necessary is reduced to one-third the conventional number, thus effecting a great reduction in cost, while not sacrificing quality of printing.

Another aspect of the invention relates to the above arrangement in which exact registry may be maintained between the plate cylinder and the etched, Anilox roll, regardless of the interchangeable gear selected for use between the impression and plate cylinders.

The present invention permits the plate cylinder to be first accurately set with respect to the impression cylinder in respect to proper printing pressure, and this adjustment includes a movement of the plate cylinder in a circumferential direction around the impression cylinder when a plate cylinder of different size is to be used; in any event, the swingable drive unit is then accurately positioned for drive engagement between the plate cylinder and impression cylinder with the proper degree of gear pressure. The Anilox roll can be held in the same exact drive ratio with the plate cylinder.

The arrangement provided by the present invention results in a versatile printing press of economical construction which is efficient and accurate in operation, and is readily setup for a variety of different printing operations.

These and other objects and advantages will appear later as this disclosure progresses, reference being had to the accompanying drawings, in which:

FIGURE 1 is a side elevational view of printing mechanism embodying the present invention, certain parts being shown as removed, broken away or in section, for clarity in the drawings;

FIGURE 2 is a "spread out," plan view of certain of the mechanism shown in FIGURE 1;

FIGURE 3 is a fragmentary, enlarged view of certain parts as shown in FIGURE 1; and

FIGURE 4 is an elevational view taken generally along the line 4—4 in FIGURE 3, certain parts being shown in section.

Referring in greater detail to the drawings, the main frame of the press includes the two sides 1 and 2 which are fabricated from heavy plate steel, the side 1 being on the operator's side of the press.

2

An impression cylinder 1C of highly polished steel is journalled in the sides 1 and 2 in anti-friction bearing assemblies (not shown) in the known manner. A large bull gear 5 is fixed to the impression cylinder for rotation with the cylinder as a unit. This bull gear is of smaller diameter than the impression cylinder and it transmits the driving power to the rest of the mechanism to be described.

Slidably mounted adjacent to the impression cylinder for adjustment relative thereto is a printing sub-assembly SA. This sub-assembly is slidable on the ways 8 of the sides 1 and 2, in a general direction towards and away from the impression cylinder as indicated by the arrow in FIGURE 1.

The sub-assembly includes a plate cylinder PC which is supported in the side walls 10 and 11 of the sub-assembly, as will later more fully appear, an Anilox roll AR, and an ink roll IR. The Anilox and ink rolls are both mounted in side walls 13 and 14 with which they form a secondary sub-assembly SSA slidably adjustable relative to the plate cylinder PC, on the ways 15 of sub-assembly SA.

The sub-assembly SA and its plate cylinder are adjustably positioned relative to the impression cylinder by the hand wheel 17 fixed to shaft 18 and the spaced gears 18a fixed thereto. Shaft 18 is journalled in bifurcated extensions of the sides 1 and 2 of the main frame. Gears 18a mesh with their respective feed screws 19 which are also rotatably supported by the main frame and are threadably engaged with their feed nuts 20 fixed to the sub-assembly. In this manner, the plate cylinder can be adjusted to the proper printing pressure with the impression roll.

The secondary sub-assembly SSA is similarly adjustable by hand wheel 22, shaft 23, gears 24, feed screws 25 and feed nuts 26 fixed on the sub-assembly. The Anilox roll can thus be adjusted for proper ink transferring pressure with the plate cylinder.

In conventional practice, if plate cylinder PC was of a 57 tooth repeat length, then its associated gear PCG would have 57 teeth, and this conventional set-up is known as a 57 repeat length printing operation. If a 58 repeat length operation was desired, it is conventional to replace the entire printing cylinder with a cylinder having a 58 repeat length together with a 58 tooth gear. Similarly, if a 56 repeat plate was desired, a 56 repeat length plate cylinder and a 56 tooth gear would be used. In other words, it was necessary to change the entire plate cylinder and gear every time it was desired to change the repeat length.

This prior practice required a large number of plate cylinders and associated gears.

The plate cylinders may be of different diameters and are interchangeable on the sub-assembly frame. For example, the plate cylinder PC shown in full lines in FIGURE 1 is a relatively large one, say for example, of a 60 inch repeat, making contact with the impression cylinder at the location 30. The smaller plate cylinder PC1 indicated by the broken lines in FIGURE 1, may be of a 10 inch repeat, and would contact the impression roll at 31, which is a distance circumferentially removed from point 30.

The plate cylinder is removably journalled in the walls 10 and 11, as follows. Upper cap portions 32, one for

each wall 10 and 11, are held by cap screws 33 in embracing relationship with the saddle portions 34 of the walls. Portions 32 and 34 are complementary and oppose one another so as to embrace the anti-friction bearing assemblies 35 in which the shaft 36 of the plate cylinder is journalled. Each end of the shaft has a diametrically reduced portion 37, 38 in which a keyway 39, 40, respectively is formed, and these keyways are located symmetrically with respect to the longitudinal center line of the press.

Any one of a number of different plate cylinder gears PCG is adapted to be secured to either portion 37 or 38 of shaft 36 by means of the keys 51.

In accordance with the present invention, it has been found possible to use a given repeat length plate cylinder not only for that specific repeat length, but also for a length slightly longer and also for a length slightly shorter; this is accomplished by permitting slipping between the plate cylinder and impression cylinder. In order to accommodate this permissible slipping, provision has been made for (1) changing gears on a given plate cylinder, (2) a special swinging drive connection between the impression cylinder and the gear selected for the plate cylinder, and (3) the same drive ratio between any given set of an Anilox roll and its matching plate cylinder and regardless of the drive between the plate cylinder and impression roll.

The invention can perhaps best be illustrated by using specific values for certain elements, but it is understood, of course, that the invention should not be limited to any given set of values, for example, in regard to gear sizes or cylinder repeat lengths.

Referring again to the gear PCG on the shaft 36, assume it is a 57 tooth repeat length so that absolute registry with the impression cylinder occurs.

Gear PCG also meshes with a gear 60 fixed on the Anilox roll shaft 61 and these gears must match perfectly in order that the etched Anilox roll is always in exact registry with the plate cylinder PC. In other words, the Anilox roll and plate cylinder must always match and when the latter is changed, a matching Anilox roll must also be used. Thus the plate cylinder and its matching Anilox roll must always register and stay on speed with one another.

Thus if we assume a 57 tooth gear is used on the plate cylinder, then a 57 tooth gear 60 must be used on the Anilox roll shaft 61.

Referring still again to the plate cylinder gear PCG, it is driven from the bull gear 5 of the impression cylinder IC by a swinging automatic compensator assembly CA, now to be described, and by means of which different sizes of plate cylinder gears can be used and proper printing pressure still maintained between the plate and impression cylinders.

The compensator assembly includes a swingable bracket 70 pivotally mounted on a stub shaft 71 fixed in the side 1 of the press frame. A compound gear 72 is rotatably mounted on one end of a shaft 73 which is threadably mounted as shown at 73a in the lower free end of bracket 70. The compound gear 72 includes a helical gear 74 and a spur gear 75 which is engageable with the selected plate cylinder gear PCG.

To the other end of shaft 73 is fixed a gear 76 which is turned by a hydraulically operated gear 77 with which it is in constant mesh. Gear 77 is actuated through its shaft 78 which is connected to a double acting hydraulic motor 79 having pressure fluid conduits 80 and 81 extending therefrom and connected to a source of pressure fluid (not shown). Plate members 79a and 79b depend from shaft 73 and act to support the motor 79, shaft 78 and its associated gear 77. This adjustment is for obtaining printing registry between the plate cylinder and the impression cylinder as will appear presently.

Secured to the other end of the pivot shaft 71 is another compound gear 82 having a wide helical gear 84 which

is engageable by gear 74 and also having a gear 85 which is in constant mesh with the bull gear 5. Thus the power train is from bull gear 5 through gears 82, 84, 74, 75 and to the gear PCG on the plate cylinder.

For the purpose of obtaining registry between the plate cylinder and the impression cylinder, the helical gear 74 is axially adjustable along the wide helical gear 84 by rotation of the gear 76 as previously mentioned. In other words, rotation of gear 76, which is slidably keyed by key 86 to shaft 73 causes shaft 73 and the compound gear 72 fixed thereto, to shift axially because of the threaded engagement 73a, to effect registration.

Means are provided for swingably adjusting the bracket 70 about its pivot axis 71 so as to bring gear 72 into proper mesh with the gear PCG selected for the plate cylinder. This means includes a hand adjusting wheel 90 fixed to shaft 91 to which is fixed the gear 92. A large gear 93 is fixed to the other end of shaft 71 and meshes with gear 92. Rotation of the hand wheel 90 in one direction or the other thus causes the bracket to swing toward or away from the plate cylinder. The bracket 94 in which the shaft 91 is journalled, is secured to the side of the main frame by cap bolts 95.

The bracket is locked in any one of its selected positions by a cap bolt 96 that extends through the arcuate slot 97 in the bracket and is threadably engaged in the side 1.

The above described drive arrangement would be used when the plate cylinder gear PCG is the same size as the plate cylinder, as previously mentioned as being a 57 tooth repeat length, for example. With the present invention, it is possible to print a longer or shorter length, say, for example, a 58 tooth repeat length, without changing the plate cylinder. This is accomplished as follows.

The compensator assembly would be loosened and swung out of mesh, and gear PCG removed from the operator's end of shaft 37 and placed on the other end, namely, on portion 38 of the shaft 36. The Anilox roll would then be reversed end-for-end in the press so that its gear 60 continued to be in mesh with its mating gear PCG.

The mounting for the Anilox roll which permits its reversal is as follows. Mounting plungers 100 and 101 are provided in the walls 13 and 14, respectively, and are held captive therein by set screws 102. By loosening the screws 102, the plungers can be withdrawn outwardly to free the shaft 61 which is mounted therein on its ball bearing assemblies 103. The roll is then reversed end-for-end and its bearing assemblies again inserted in the open ends of the plungers which are then secured in place. Gear 60 is now located at the opposite side and again in mesh with gear PCG. In order to permit this Anilox roll reversal, the roll must be symmetrical with the impression cylinder in either of its positions.

The above means and method of reversing the Anilox drive end is a practical one which can be done quickly; alternatively however, it would be possible to change the gear 60 to the other end of the shaft 61 to effect mesh with the gear PCG.

Instead of the 57 tooth gear PCG, a different size gear can be installed on the plate cylinder shaft, for example, a 56 or a 58 tooth gear. Gears having a greater differential than this in the number of teeth have not proved satisfactory because of the excessive skidding necessary between the cylinders, which results in poor printing. It has been found possible, however, to use gears of one tooth more or less than the gear which matches exactly with the repeat length of the plate cylinder.

In any event, after the 57 tooth gear PCG has been fixed on the other end portion 38 of the plate cylinder shaft, and the Anilox roll reversed, a new gear PCG 58 (not shown), say one with 58 teeth, would be installed on portion 37 of shaft 36 for mesh with gear 75. The compensator assembly, that is gear 75, would then be brought into proper mesh with the gear PCG 58.

Different sizes of plate cylinders, of course, will also

need to be interchangeable in the press but the total number of cylinders required has been reduced to one-third of those conventionally required for a comparable range of work.

When a different size plate cylinder is installed, the printing pressure between this plate cylinder and impression cylinder can be adjusted, which will have the effect of creating a nip printing couple at a different circumferential location on the impression cylinder, as shown in FIGURE 1. Nevertheless, after this adjustment has been made, the compensator assembly can accurately and quickly bring the new drive gear into proper driving engagement and pressure with the swinging gears and consequently the bull gear.

Various modes of carrying out the invention are contemplated as being within the scope of the following claims particularly pointing out and distinctly claiming the subject matter which is regarded as the invention.

I claim:

1. Rotary printing press mechanism of the type having a main frame and an impression cylinder rotatably mounted in said main frame and a bull gear secured therewith, and a plate cylinder shiftably mounted for engagement with said impression cylinder and having a shaft extending from each end, the improvement comprising, a removable gear selectively fixable on one end of said shaft or the other and having a number of teeth corresponding to the repeat length of said plate cylinder, at least one interchangeable gear adapted to be removably fixed on said one end of said shaft and having a number of teeth different from the repeat length of said plate cylinder, an Anilox roll engageable with and of a diameter which matches said plate cylinder, gear means on said Anilox roll, and means for removably mounting said gear means at either end of said Anilox roll for meshing with said removable gear when the latter is fixed on either end of said shaft, a first gear mounted on said main frame and in constant mesh with said bull gear, and a second gear swingably mounted on said frame about the center of said first gear and in constant mesh therewith, said second gear being swingably adjustable for engagement with that gear which is removably fixed on said one end of said plate cylinder shaft.

2. Mechanism as set forth in claim 1 further characterized in that said first and second gears are compound gears each having a helical gear in mesh with one another, and means for axially adjusting said helical gears relative to one another to effect printing registration between said cylinders.

3. Mechanism as defined in claim 1 further characterized in that said last named means includes means for removably mounting said Anilox roll in said frame in either end-for-end position in which it is laterally symmetrical with said plate and impression cylinders, to permit said meshing of said Anilox roll gear means with said removable gear.

4. Rotary printing press mechanism comprising, a main frame, an impression cylinder rotatably mounted in said frame and having a bull gear secured therewith, a plate cylinder shiftably mounted for engagement with said impression cylinder and having a shaft extending from each end, a removable gear selectively fixable on one end of said shaft or the other and having a number of teeth corresponding to the repeat length of said plate cylinder, at least one interchangeable gear adapted to be removably fixed on said one end of said shaft and having a number of teeth different from the repeat length of said plate cylinder, an Anilox roll engageable with and matching said plate cylinder, gear means on said Anilox roll, and means for removably mounting said gear means at either end of said Anilox roll for meshing with said removable gear when the latter is fixed on either end of said shaft, a first gear mounted on an axis on said main frame and in constant mesh with said bull gear, and a second gear swingably mounted on said frame about said axis and in constant mesh with

said first gear, said second gear being swingably adjustable for engagement with that gear which is removably fixed on said one end of said plate cylinder shaft.

5. Rotary printing press mechanism comprising, a main frame, an impression cylinder rotatably mounted in said frame and having a bull gear secured therewith, a plate cylinder shiftably mounted for engagement with said impression cylinder and having a shaft extending from each end, a removable gear selectively fixable on one end of said shaft or the other and having a number of teeth corresponding to the repeat length of said plate cylinder, at least one interchangeable gear adapted to be removably fixed on said one end of said shaft and having a number of teeth different from the repeat length of said plate cylinder, an Anilox roll engageable with and matching said plate cylinder, gear means on said Anilox roll, and means for removably mounting said gear means at either end of said Anilox roll for meshing with said removable gear when the latter is fixed on either end of said shaft, a first compound gear mounted on an axis on said main frame and in constant mesh with said bull gear, a second compound gear swingably mounted on said frame about said axis and in constant mesh with said first compound gear, said second gear being swingably adjustable for engagement with that gear which is removably fixed on said one end of said plate cylinder shaft, each compound gear having a helical gear which mesh with one another, and means for axially adjusting one helical gear relative to the other to effect printing registry between said plate and impression cylinders.

6. Rotary printing press mechanism comprising, a main frame, an impression cylinder rotatably mounted in said frame and having a bull gear secured therewith, a plate cylinder shiftably mounted for engagement with said impression cylinder and having a shaft extending from each end, a removable gear selectively fixable on one end of said shaft or the other and having a number of teeth corresponding to the repeat length of said plate cylinder, at least one interchangeable gear adapted to be removably fixed on said one end of said shaft and having a number of teeth different from the repeat length of said plate cylinder, an Anilox roll engageable with and of a diameter which matches that of said plate cylinder, gear means fixed to one end of said Anilox roll, means for removably mounting said Anilox roll in said frame in either end-for-end position whereby said gear means can mesh with said removable gear when the latter is fixed on either end of said shaft, a first gear mounted on an axis on said main frame and in constant mesh with said bull gear, and a second gear swingably mounted on said frame about said axis and in constant mesh with said first gear, said second gear being swingably adjustable for engagement with that gear which is removably fixed on said one end of said plate cylinder shaft.

55. 7. Rotary printing press mechanism comprising, a main frame, an impression cylinder rotatably mounted in said frame and having a bull gear secured therewith, a plate cylinder having a shaft extending from each end, means for slidably mounting said plate cylinder toward and away from said impression cylinder for adjusting the printing couple therebetween, a removable gear selectively fixable on one end of said shaft or the other and having a number of teeth corresponding to the repeat length of said plate cylinder, at least one interchangeable gear adapted to be removably fixed on said one end of said shaft and having a number of teeth different from the repeat length of said plate cylinder, an Anilox roll engageable with and matching said plate cylinder, gear means secured to one end of said Anilox roll, means for removably mounting said Anilox roll in said frame in either end-for-end position whereby said gear means can mesh with said removable gear when the latter is fixed on either end of said shaft, a first compound gear mounted on an axis on said main frame and in constant mesh with

said bull gear, a second compound gear swingably mounted on said frame about said axis and in constant mesh with said first compound gear, said second gear being swingably adjustable for engagement with that gear which is removably fixed on said one end of said plate cylinder shaft, each compound gear having a helical gear which mesh with one another, and means for axially adjusting one helical gear relative to the other to effect printing registry between said plate and impression cylinders.
